Patented May 23, 1922.

UNITED STATES PATENT OFFICE.

CHARLES G. WALKER, OF HIGHLAND PARK, MICHIGAN.

BASE FOR HEATERS OR THE LIKE.

1,416,916.

Specification of Letters Patent. Patented May 23, 1922.

Application filed August 1, 1921. Serial No. 438,377.

To all whom it may concern:

Be it known that I, CHARLES G. WALKER, a citizen of the United States of America, residing at Highland Park, county of Wayne, and State of Michigan, have invented a new and useful Improvement in Bases for Heaters or the like, of which the following is a specification, reference being had therein to the accompanying drawings.

10 My invention relates to a base for heaters or the like, and is more particularly designed for hot water heaters of the type known as "instantaneous heaters."

In the operation of "instantaneous" or automatic water heaters, it is a well known fact that the action of the heat from the various gas jets or other heating means upon the cold pipes or coils in the heaters causes a condensation of water on the outside of the coils. This condensation, in turn, causes the water formed on the outside of the coils to drop off the same on to the base of the heater.

This water which is formed by condensation on the coils possesses an acid which, when the water drips off on the base of the heater, eats the same away, with the consequent result that a new base for the heater must be supplied. When this happens it is, 30 of course, impossible to use the heater until it has been repaired. Also, such repairs are very costly.

It is the primary object of my invention to overcome the delays and costs of the above mentioned disadvantages by the construction of a relatively cheap and simple base for such heaters, and one which will last the life time of the heater.

These and other objects and advantages are shown in the arrangement, combination and construction of the various parts of my improved device as described in the specification, claimed in my claims and shown in the accompanying drawings, in which:

45 Fig. 1 is a side elevation of my improved base, showing a standard heater thereon.

Fig. 2 is a top or plan view of my improved base.

50 Fig. 3 is a central vertical sectional view of the same taken on line 3-3 of Fig. 2.

Fig. 4 is a side elevation showing a modified form of my improved base.

I have shown for illustration a standard type of water heater 1 mounted upon my improved base 2. I wish it understood, however, that any form of heater may be used

with my base by merely changing structural details of the base to fit the heater.

I provide a groove or trough 8 on the top of my improved base, into which the bottom of the heater shell 4 is placed. While I have herein shown this groove or trough to be circular, it should be understood that it may be made angular, oval or any other shape to conform to the shape of the bottom portion of the heater shell which is to rest thereon.

I also provide a bowl or cavity 5 in the top of my improved base and a drain 6 connecting therewith and extending out and away from the base.

70 My improved base is preferably constructed of concrete, so that the acids and water which condense on the coils in the heater and drip downward thereon will not and cannot effect it in the least. What actually happens is that these acids and water will fall in the bowl or cavity 5 and be immediately carried away through the drain 6.

75 In the modified form of base shown in Fig. 4, I have adapted my base to a heater wherein the doors 7 thereof are located practically at the bottom of the shell 4. In order to accomplish this, I cut away that portion of the base, to the depth of the groove or trough 8, which lies in front of the said doors, as shown at 9, so that the doors may be opened and closed at will without being obstructed by the front side of the groove or trough 8.

90 It is sometimes desirable to make the connection between the base 2 and shell 4 substantially air tight and in order to do this a layer of cement or other suitable packing may be laid around the outer edge of the groove 8 after the shell 4 is placed therein.

95 It will thus be seen that I have provided a base, adaptable for use on any heater, of simple and cheap construction, and which will not be affected by or corroded from acids or condensed water and which will last during the life time of the heater.

100 Some changes may be made in the arrangement and combination of the various parts of my improved device without departing from the spirit of the invention therein and it is my intention to cover by my claims such changes as may be reasonably included within the scope thereof.

110 What I claim is:

1. A base for heaters or the like, consisting of a concrete mass having means for

locating the shell of the heater thereon and means therein for receiving the drippings from the heater.

5. A base for heaters or the like, consisting of a concrete mass having a groove therein conforming in contour to the size and shape of the heater shell and into which said shell is adapted to be positioned.

10. A base for heaters or the like having a groove thereon adapted to receive the heater shell, a portion of the outer side of said groove being cut away to permit the open-

ing and closing of doors located on said shell.

15. 4. A base for heaters or the like, consisting of a concrete mass having a groove therein conforming in contour to the size and shape of the heater shell and into which said shell is adapted to be positioned, whereby the joint between said base and said shell may 20 be made substantially air tight by filling in said groove after said shell is placed therein.

CHARLES G. WALKER.
